TUBE HOLDER

Dalton Stockwell, Philadelphia, Pa.

Application September 9, 1937, Serial No. 163,119

1 Claim. (Cl. 221—60)

My invention relates to improvements in tube holders for use in holding and ejecting the contents from collapsible tubes containing tooth paste, shaving cream, or the like.

5 The invention is directed primarily toward providing an efficient, inexpensive device of this character equipped to securely hold a tube in inverted position therein and embodying improved means for collapsing the tube to eject therefrom 10 the exact quantity of the contents desired and means for readily attaching the device to a wall or the like in position for convenient access to the neck of the tube.

To the accomplishment of the above, and sub- 15 ordinate objects, presently appearing, a preferred embodiment of my invention has been illustrated in the accompanying drawings, set forth in detail in the following description, and defined in the claim appended hereto.

20 In said drawings:

Figure 1 is a view in side elevation of a holder constructed in accordance with my invention;

Figure 2 is a view in front elevation;

Figure 3 is a view similar to Figure 1 with the 25 front section in opened position;

Figure 4 is a view in horizontal section taken on the line 4—4 of Figure 1, looking downward;

Figure 5 is a fragmentary view in vertical 30 transverse section taken on the line 5—5 of Figure 4 looking in the direction indicated by the arrows;

Figure 6 is a view in vertical section of the front section;

Figure 7 is a view in side elevation of the key; 35 and

Figure 8 is a view in perspective of a clamping member.

Referring to the drawings by numerals, the 40 holder of my invention comprises, as the basic elements thereof, a pair of front and rear box-like sections 1 and 2 open at their ends, a bottom plate-like member 3, and a similar top member 4, all preferably of suitable light sheet metal with the exception of the front section 1, which is provided with a glass panel front 5. The bottom member 3 is formed with upright side flanges 6. The rear section 2 is fitted at one end between 45 said flanges 6 adjacent one edge of the member 3 and suitably secured thereto in right angular position with its other end uppermost. The front section 1 is hinged at one end, as at 7, to the flanges 6, adjacent the opposite edge of said member 3, to fold into and form parallel relation to the rear section 2 with its open side opposed to the 50 open side of the latter. The front section 1 is

hinged to space the same from the rear section 2 so that in its parallel relation, or in other words, its closed position, said sections are spaced apart to form a pair of longitudinally extending slots 8 between the same at opposite sides thereof. The 5 top member 4 is provided with side flanges 9 and is secured to the free end of the front section 1 to close the same and take over the free end of the section 2 to close the latter in the closed position of the section 1. The rear section 2 is provided, 10 at the back thereof, with an upper tab, or ear, 10, extending from its top or free end for the attachment of the device to a wall 11, as by a screw 12. A pair of similar tabs 13 extend laterally and rearwardly from opposite sides of the 15 section 2, adjacent the opposite end thereof, for further securing of the device to the wall 11, as by screws 14, said tabs 13 spacing the device from the wall 11 so that it assumes a forwardly and downwardly inclined position. A spring 20 catch 15 extends from the tab 10 for cooperation with a button 16 on the top member 4 to lock the front section 1 in closed position. The bottom member 3 is apertured centrally, as at 17, to receive the neck 18 of a collapsible tube 19 so that 25 the latter may be disposed in the holder in upright position, said neck extending below the bottom member 3, in which position said neck is readily accessible and arranged to receive the usual closure cap 18'. The front section 1 has a horizontal cross-bar 29 therein adjacent its lower end to 30 guard the glass panel 5 against contact with the tube 19 during positioning of the latter.

A key 20 is provided for cooperation with the slot 8, in the closed position of the section 1, and 35 the tube 19 to collapse the same. The key 20 comprises a round shank 21 adapted to extend through the slot 8 and to roll along the edges of the latter, said shank being longitudinally slotted, as at 22, so that the tail end of the tube 19 may 40 be inserted thereinto. At one end, the shank 21 is provided with a finger grip 23, and at its other end with a collar 24. As will be clear, the finger grip 23 and the collar 24 function to prevent key 20 from slipping endwise out of said slot 8. 45

A particular feature of my invention is the following means for holding the tube 19 in position. Extending through the back of the rear section 2 for sliding engagement with the upper face of the bottom member 3 is a rod-like clamping 50 member 25 having a front eye-like end 26 and a rear threaded end 27 extending rearwardly of said section 2. The front eye-like end 26 is designed to take over the neck 18 of the tube 19 and the rear end 27 is provided with a knurled thumb 55

nut 28 by manipulation of which the clamping member may be drawn rearwardly until the neck 18 is clamped between the eye-like front end 26 and the opposite edge of the aperture 17, as 5 best illustrated in Figure 5.

As will be understood when the tube 19 is positioned as described in the foregoing, the tail end thereof is inserted through the slot 22 in the key 20 and wound thereon by turning of the said key, 10 under manipulation of the finger grip 23, whereby the contents of the tube 19 are squeezed therefrom in the usual manner. When the contents of the tube 19 are completely discharged, the front section 1 may be swung to opened position, the 15 clamping member 25 loosened and the tube 19 readily removed and replaced by a full one.

The structural details, operation and advantages of my invention will, it is believed, be clear from the foregoing without further explanation.

20 Manifestly, the invention, as described, is susceptible of modification without departing from

the inventive concept, and right is herein reserved to all such modifications falling within the scope of the subjoined claim.

What I claim is:

In a device for holding collapsible tubes, a casing having a bottom member apertured centrally for the projection of the neck of a tube therethrough, and sides having a pair of vertically extending slots therein, a key extending through said slots for rotation therein and provided with 10 means for attaching the tail end of the tube thereto whereby upon rotation of said key said tube will be wound on said key, and means for clamping the neck of the tube to the edge of the aperture and comprising a bar slidably mounted in 15 the wall of the casing and having a front eye-like end adapted to take over said neck, and a threaded end extending outside said wall, and a thumb nut threaded on said end.

20

DALTON STOCKWELL.
